UNITED STATES PATENT OFFICE.

GEORGE COOK, OF BUFFALO, NEW YORK.

SUPERHEATER FOR BOILERS.

Application filed April 19, 1918. Serial No. 229,607.

To all whom it may concern:

Be it known that I, GEORGE COOK, a citizen of the United States, residing at Buffalo, in the county of Erie and State of New York, have invented a new and useful Superheater for Boilers, of which the following is a specification.

This invention has reference to superheaters for boilers, and its object is to provide a superheater structure along the general lines set forth in Patent No. 1,140,956 granted to me on May 25, 1915.

One of the objects of the invention is to provide means whereby the superheater elements may be readily replaced from time to time without the necessity of dismantling the structure to any material extent.

The invention will be best understood from a consideration of the following detailed description taken in connection with the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claims.

50 In the drawings:

Figure 1 is an end elevation of so much of a locomotive as is needful for an understanding of the invention, with the shell of the locomotive boiler shown in cross section.

Figure 2 is a longitudinal section on the line 2—2 of Figure 1.

Figure 3 is a detail elevation of an arrangement for controlling the admission of steam to the locomotive cylinders.

Figure 4 is a longitudinal section with some parts in elevation, showing a detail of construction appearing in Figure 2 but on a larger scale.

Figure 5 is a section of a header on the line 5—5 of Figure 2.

Figure 6 is a section on the line 6—6 of Figure 4.

Referring to the drawings, there is shown a boiler 1 without any attempt to show any special construction thereof, and this boiler is assumed to be a locomotive boiler with cylinders 2, 3 on opposite sides, as is customary. The boiler is provided with the usual saddle 4 which forms no part of the invention but is mentioned merely for the purpose of locating some other parts.

Extending between the customary flue sheets 5, 6 of the boiler are fire tubes or flues 7 which may be of ordinary construction and require no special description. In conjunction with the fire tubes 7 are other larger fire tubes 8 utilized in connection with the superheater of the invention. Those ends of the tubes adjacent to the fire box of the boiler may be the same size as the tubes 7, while the major portion of the length of the tubes 8 is larger to accommodate certain structures to be described. Located in each fire tube 8 is a superheater element preferably comprising an elongated shell 9, which, as will hereinafter appear, constitutes a superheater compartment for steam. This shell is shown in Figures 2 and 4 as entering the fire tube 8 and extending to a point near the small end thereof and adjacent to such small end has a conical terminal portion 10 having a threaded extension 12 adapted to removably receive a cap 13 which snugly fits the conical portion of the shell to protect the same against excessive heat. The other end of the shell 9 is provided with a head 11 which may be firmly secured therein as by welding or the like.

The head 11 may project for a short distance beyond the exit end of the fire tube containing it and within the shell 9 the head 11 carries a pipe 14 of a length to reach approximately to the reduced end 10 of the shell 9. The pipe 14 is readily introduced into the shell 9 through a suitable hole 75 formed in the head 11 and then tightly expanded therein, or may be otherwise secured, as for instance, before the head 11 is made fast to the corresponding end of the shell 9. In line with the pipe 14 is another pipe 15 80 and secured in the head 11 alongside of the pipe 15 is still another pipe 16, the pipes 15 and 16 entering the head 11 from the outside and the pipe 16 terminating at the head 11. In order to accommodate the two pipes the superheater shell 9 may be more or less elliptical or flattened at the end containing the head 11 and the shell 9 may have exterior spacers or feet 17 for engaging the inner wall of the fire tube 8. These feet may be arranged divergently and serve to space the shell 9 from the inner wall of the fire tube 8 in which the shell is located to permit ample room about the shell for the flow of the hot gasses of combustion.

Located in the smoke chamber of the boiler forward of the front end of the fire

tube assembly is a header 18 of hollow construction with two ends 19 and top and bottom members 20 and 21 respectively, the header being preferably although not necessarily of generally rectangular form. Within the header is an intermediate web 22 extending throughout the length of the header dividing the latter into outer and inner continuous chambers 23, 24 respectively. Entering the chamber 23 at an appropriate point is a pipe 25 leading to the flue or tube sheet 5 where it is joined to the dry pipe 26 coming from the usual steam dome 27 of the boiler. While the pipe 25 might be made in one piece with the header, it is preferably made separate therefrom and joined thereto by bolts 28 or otherwise. Within the smoke chamber of the boiler on opposite sides thereof are tracks 29 carrying rollers 30 supporting hangers 31 made fast to ears 32 on the sides of the header so that by disconnecting the pipe 25 from the pipe 26 the header may be readily moved toward the front of the smoke box away from the tube sheet 5 to give room for repairs or other purposes.

The pipes 15 and 16 extend forwardly through the space defined by the header and have return bends which terminate in heads 33 adapted to fit in seats 34 about the ports 35, entering the compartments 23 and 24 at the front of the header. The heads 33 of the pipes 15 and 16 are held in place by clamp plates 36 secured to the header by a bolt 37 having its head seated in a groove 38 to permit a limited adjustment and also permitting the use of a single bolt if such be found desirable to hold a pair of pipes 15 and 16 in place.

At an appropriate point the chamber 24 is connected through a hollow boss or enlargement 39 with another pipe 40 in turn connected by a pipe 41 through the side of the boiler shell to a valve 42. Branched off from the valve 42 are pipes 43 and 44 respectively, the pipe 43 leading into the steam chest of the cylinder 2 and the pipe 44 being carried beneath the boiler to the steam chest of the cylinder 3, the pipe 44 being sustained by clips 45 in turn carried by the saddle 4. Communicating with the pipe 44 is another valve 46 connected by a pipe 47 to the pipe 25. On the header side of the point where the pipe 47 joins the pipe 25 there is a valve 48 which may be readily reached from the outside of the boiler so that communication between the steam dome 27 and the header 18 may be cut off when desired. The valves 42 and 46 are under the control of appropriate reach rods 49 which may be assumed to extend to the cab of the locomotive so as to be under the control of the engineer, or any other arrangement may be provided for controlling these valves. In order to prevent harmful

pocketing of condensed steam the pipe 44 is shown as provided with a relief valve 50 and a drain cock 51, the relief valve 50 being automatic in its action while the drain cock 51 may be opened and closed at will.

When the boiler is producing steam and the valve 48 is opened, and further steam is being used in the cylinders 2 and 3, the steam directly from the boiler passes into the chamber 23 of the header and is distributed about the same and through the ports 35 of the chamber 23 to the several pipes 16. The steam enters that end of each shell 9 remote from the small end thereof and flows to said small end before it can reach the open end of the pipe 14, wherefore, the steam is progressively superheated until it reaches the hottest portion of the shell 9 which is that portion first engaged by the hot gases of combustion. Then the steam passes through the pipes 14 and 15 through the compartment 24 and by way of the enlargement 39 and pipe 40 to the valve 42 from which the steam is distributed by the pipe 43 to both the cylinder 2 and by the pipe 44, the last named pipe conducting the steam to the cylinder 3. It will be understood that in the practical embodiment of the invention all those pipes exposed outside of the boiler and subjected more or less to the chilling effect of the atmosphere may be covered with some heat insulating material. This being a common practice it is deemed unnecessary to either show or particularly describe such expedient.

Under ordinary conditions of use the superheater flues 8 break down or burn out much more frequently than do the flues 7 and must be renewed oftener. Heretofore, it has been found necessary to dismantle and move the header 18 out of the way in order to repair or replace even one of the flues 8. With the arrangement shown in the drawings, any one or more of the flues 8 may be readily reached and repaired or removed and replaced without disturbing the header at all, and in most instances without disturbing any pair of pipes 15 and 16 except the pair or pairs belonging to the parts to be fixed. By a proper disposition of the pipes and flues it is quite feasible to reduce the dismantling to a single pair of pipes 15 and 16 and the parts directly connected therewith. Even in the arrangement shown in the drawings any superheater element may be reached and withdrawn and replaced without disturbing more than two of the pairs of pipes 15 and 16.

In the ordinary operation of the structure with the superheater working the valve 46 is closed and the valve 42 is opened. Suppose, however, that for some reason the superheater is put out of commission, then the valves 48 and 42 are closed and the valve

46 is opened, whereupon, steam directly from the steam dome 27 will flow by way of the pipe 26, pipe 25, pipe 47 to the pipe 44 and flow therefrom directly to the cylinder 3 and by way of the pipe 43 to the cylinder 2, thus permitting the running of the locomotive from the place where the superheater went out of commission to a point where repairs may be made. Ordinarily such a contingency would cause the stalling of the engine until help could be obtained.

What is claimed is:—

1. In a superheater for fire tube boilers having a smoke box, a continuous rectangular header divided into a pair of adjacent continuous compartments, one compartment surrounding the other, said header being arranged in the smoke box and defining a space between the inner walls thereof, a plurality of relatively large fire tubes in the boiler, the axes of which pass through said space within the header, superheater elements removably mounted in the enlarged fire tubes, pipes connecting each of said elements with both of said compartments, said pipes extending through the space defined by said header and having return bends in front of said header and connected to the front side thereof, and means for conducting steam to and from said compartments.
2. In a superheater for locomotive boilers, a continuous substantially rectangular header substantially rectangular in cross section arranged in the smoke box, said header defining a space between the inner walls thereof, a continuous partition dividing the header into an outer saturated steam compartment and an inner superheated steam compartment, a plurality of enlarged fire tubes in the boiler, the axes of which pass through said space, superheater elements in some of said fire tubes, a pair of pipes connected to each of said elements extending

forwardly through the space defined by the header and removably connected to the front wall of the header, one pipe communicating with the saturated steam compartment and the other with the superheated steam compartment, and conduits for conducting steam to and from said compartments.

3. In a superheater for locomotive boilers, a continuous rectangular header in the smoke box defining a rectangular space, a continuous web in said header dividing it into two compartments, one surrounding the other, slots being provided in the front wall of said header in the plane of said web, superheater elements in some of the fire tubes of the boiler, a pair of pipes connecting each of said elements with the respective compartments of the header passing through the space defined by said header and connected through the front wall thereof, and means in said slots for securing said pipes in steam tight engagement with said header.

4. In a superheater for boilers, a fire tube of enlarged diameter having a reduced end near the fire box, a shell within said fire tube, means to hold said shell spaced therefrom, said shell having a reduced end near the reduced end of the fire tube and exteriorly screw threaded, a cap provided with internal threads adapted to engage the threads upon said shell end to protect the same, means closing the other end of the shell, a header, pipes leading from the header to said shell, one of said pipes delivering boiler steam to the reduced end of the shell, the other conducting superheated steam from the opposite end of the shell.

In testimony, that I claim the foregoing as my own I have hereto affixed my signature.

GEORGE COOK.
